UNITED STATES PATENT OFFICE.

WILLIAM R. SHARP, OF NEW PHILADELPHIA, OHIO.

METER.

SPECIFICATION forming part of Letters Patent No. 766,535, dated August 2, 1904.

Application filed April 5, 1904. Serial No. 201,632. (No model.)

To all whom it may concern:

Be it known that I, WILLIAM R. SHARP, a citizen of the United States, residing at New Philadelphia, in the county of Tuscarawas and State of Ohio, have invented certain new and useful Improvements in Meters; and I do hereby declare that the following is a full, clear, and exact description of the same, reference being had to the annexed drawings, making a part of this specification, and to the numerals of reference marked thereon.

The object of the present invention is to provide a meter that will measure the water of condensation in pounds or liquid measure, thereby measuring the amount of steam employed or used for heating purposes.

Figure 1 is a vertical horizontal section. Fig. 2 is a perspective view of the drip or dumping pan, showing the casing removed and illustrating the water-of-condensation spout in proper relative position, also showing the catch-trough. Fig. 3 is a transverse section of one of the vertical sides of the casing, showing an edge view of the meter ratchet-wheel and casing, also showing a partial end view of the dumping-pan.

Similar numerals of reference indicate corresponding parts in all the figures of the drawings.

In the accompanying drawings, 1 represents the casing, which may be of any desired size, and in which casing is located the dumping-pan 2, said dumping-pan being pivotally mounted upon the fulcrum-rib 3, and for the purpose of preventing friction said fulcrum-rib is provided with a comparative sharp edge, which sharp edge rests in the notches 4, formed in the supports 5, which supports are fixed to the casing in any convenient and well-known manner. The dumping-pan 2 is so formed and mounted that its normal position will be that shown in Fig. 2 and in full lines, Fig. 1.

For the purpose of stopping or holding the dumping-pan in proper position the stop-screw 6 is provided, said stop-screw being so located that the bottom or under side of the dumping-pan will strike the top or upper end of the screw 6, as illustrated in Fig. 1.

From the radiator or radiators leads the water-of-condensation pipe 7, and upon the

inner face of the casing and opposite the pipe 7 is located the discharge-pipe section 8, which pipe is curved, as illustrated in the drawings, and provided with an elongated outlet 9, said pipe 8 being curved for the purpose of better 55 conducting the water into the dumping-pan 2 and into the temporarily-holding water-pan 10.

To the dumping-pan 2 is pivotally attached the detent 11, which detent is so formed that when the dumping-pan is in a tilted position, as illustrated in dotted lines, Fig. 1, said detent will engage one of the teeth 12, formed upon the meter-ratchet 13, and after the water contained in the dumping-pan has escaped 65 therefrom said dumping-pan will assume its normal position, and in assuming its normal position the detent 11 will move downward with the dumping-pan, thereby turning the ratchet-wheel 13, said ratchet-wheel being 70 provided with a predetermined number of teeth, so as to give the ratchet-wheel 13, together with the meter-shaft 14, the desired part of a revolution, the most convenient division being one-tenth of a revolution to each 75 downward tilt of the dumping-pan at the detent end thereof.

It will be understood that in order to provide for the automatic tilting of the dumping-pan when empty it must be so balanced that 80 the greater weight of the dumping-pan will be upon the end provided with the detent 11; but when a certain quantity of water is conveyed to the dumping-pan the greater weight will be upon the opposite end of the dumping-pan from that to which the detent is attached, 85 thereby causing the dumping-pan to tilt into the position illustrated in dotted lines, Fig. 1, and when in that position the water will escape or run from the dumping-pan. 90

It will be understood that owing to the fact that a certain predetermined amount of water must be contained in the dumping-pan before it is tilted the meter proper will register the number of tilts, thereby providing a means 95 for calculating the amount of condensed water that has passed through the pipe 7 and from thence through the dumping-pan and out the discharge-pipe 15.

The mechanism or train of wheels employed 100

in a meter is not here illustrated, owing to the fact that they form no particular part of the present invention, except that a meter operated by the ratchet-wheel 13 and the detent 5 11 is to be employed.

For the purpose of stopping the tilting movement of the dumping-pan at the time it is desired to discharge the water therefrom the stop-screw 16 is employed, which stop-screw is so adjusted that when the delivery end of said dumping-pan comes in contact with the top or upper end of said stop-screw it will have the proper incline to permit the water to be discharged from said dumping-pan.

It is well understood that during the time various radiators are filled with steam the water of condensation is continuously flowing, and in order to prevent any water from escaping the dumping-pan during the time it is being emptied the pivoted trough or receptacle 10 is employed, which trough is so located that its normal position will be that shown in Figs. 1 and 2, which position permits the water to flow from the trough 17 into the dumping-pan 2; but during the time said dumping-pan is in the position illustrated in dotted lines, Fig. 1, the trough or receptacle will be in the position illustrated in dotted lines, Fig. 1, said position being such that the water will be confined in said receptacle, and when the dumping-pan assumes its normal position the receptacle 17 will fall by gravity into the position illustrated in Fig. 1, thereby allowing the water which has accumulated in the trough during the time the dumping-pan is being emptied to flow from said receptacle 17 into the dumping-pan, by which arrangement all the water of condensation is measured and none escapes or passes through the pipe 15 that has not passed over the dumping-pan 2.

In order to reduce the friction and to allow the easy movement of the dumping-pan and the receptacle 17, the antifriction-roller 18 is provided, which antifriction-roller is so located that as the detent end of the dumping-pan is elevated the roller 18 will come in contact with the bottom or under side of the receptacle 10.

It will be understood that the receptacle 10 should be pivoted a short distance to one side of its longitudinal center, thereby providing a means for the automatic tilting of said receptacle when not engaged with the roller 18.

By the use of the dumping-pan 2 and operatively connecting said dumping-pan with

a meter mechanism the amount of steam can be measured that has passed through a radiator or any given number of radiators the condensation-pipes of which are so connected that all of the water of condensation will be delivered to the dumping-pan, by which arrangement I am enabled to provide a means for actually determining the amount of steam employed to heat any particular building or any room of a building.

If in the event a heating system is employed to heat a number of buildings or different places, it will be understood that a meter such as illustrated can be employed for each building or room, if desired, this being very desirable where a central plant or a bank of boilers is employed to furnish heat for city use or for other places wherein the heat is to be distributed to various places.

Having fully described my invention, what I claim as new, and desire to secure by Letters Patent, is—

1. The combination of a casing, a dumping-pan located therein and provided with a fulcrum-rib, a support for said rib and pan the pan normally located at an angle to a horizontal plane, a detent pivotally attached to the dumping-pan, and a ratchet-wheel adapted for engagement with the detent, a receptacle located over the inflow end of the dumping-pan and pivoted at one side of its gravity center, adjustable stops adapted to limit the movements of the dumping-pan, and a registering device operated by said ratchet-wheel, substantially as and for the purpose specified.

2. The combination of a casing, a dumping-pan located therein and pivotally mounted between its ends, said pan normally located at an angle to a horizontal plane, a detent pivotally attached to the inflow end of the dumping-pan and a ratchet-wheel for engagement with the detent, an antifriction-roller connected to the dumping-pan and carried thereby, a receptacle located over the inflow end of the dumping-pan and pivoted at one side of its gravity center, means for limiting the tilting of the dumping-pan, and a registering device operated by said ratchet-wheel, substantially as and for the purpose specified.

In testimony that I claim the above I have hereunto subscribed my name in the presence of two witnesses.

WILLIAM R. SHARP.
